(57) **CLAIM**

The ornamental design for a vertical rack mount kit for desktop network appliances, as shown and described.

DESCRIPTION

FIG. 1 is a perspective view of a vertical rack mount kit for desktop network appliances showing our new design thereof;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines depict portions of the vertical rack mount kit for desktop network appliances that form no part of the claimed design.

1 Claim, 7 Drawing Sheets
